UNITED STATES PATENT OFFICE

170,345

ASH TRAY

James V. Vevirit, Kenmore, N. Y., assignor to
McDonald Products Corporation, Buffalo, N. Y.,
a corporation of New York

Application March 29, 1952, Serial No. 19,111

Term of patent 14 years

(Cl. D85—2)

To all whom it may concern:

Be it known that James V. Vevirit, a citizen of the United States, residing at Kenmore, New York, has invented a new, original, and ornamental Design for an Ash Tray, of which the following is a specification, reference being had to the accompanying drawing, forming a part hereof.

Fig. 1 is a perspective view of an ash tray, showing the new design; and

Fig. 2 is a side elevation thereof, with the right hand portion broken away and shown in cross section.

I claim:

The ornamental design for an ash tray, as shown.

JAMES V. VEVIRIT.
